ANNUNCIATOR SYSTEM

Jon J. McNeill, Pittsburgh, Pa., assignor to Westinghouse Electric Corporation, East Pittsburgh, Pa., a corporation of Pennsylvania

Filed Jan. 2, 1958, Ser. No. 706,687

5 Claims. (Cl. 340—213)

This invention relates to annunciator systems of a type which embodies static logic elements, such for example as saturable core or other static switching devices, to perform the various annunciator functions.

An object of this invention is to provide an annunciator having static logic elements which cooperate with a flasher to produce a flashing light for indicating an abnormal condition in a monitored circuit.

Another object of this invention is to provide an annunciator having static elements which cooperate with a pulse producing device to provide a pulsing signal for indicating an abnormal condition at a monitored point.

It is a further object of this invention to provide an annunciator having static elements cooperating to actuate a first indicator or alarm, and cooperating with a pulse producing device to actuate a second indicator of a different type.

It is a further object of this invention to provide an annunciator having saturable core or other static logic elements cooperating to actuate an audio signal and to flash or cause other changes in the illumination of a light for indicating an abnormal condition in a monitored circuit.

Still another object of this invention is to provide an annunciator system having saturable core static logic elements which respond to an abnormal condition in a monitored circuit to actuate an audio indicator and a flashing visual indicator, and which thereafter responds to an acknowledge signal to deactivate the audio indicator and simultaneously switch the flashing visual indicator to a steady visual indicator.

Another object of this invention is to provide an annunciator system having saturable core static logic elements which cooperate with impedance means to actuate a dim light indicator in response to normal conditions at a monitored point and to actuate a flashing or bright light indicator in response to an abnormal condition at the monitored point.

An additional object of the invention is to make possible the use of a low energy output flasher of the static type, by connecting the flasher at the input side of the amplifiers which feed the lamps, so that the flasher does not have to handle the power for lighting the lamps.

Other objects of the invention will in part be obvious and will in part appear hereinafter.

The invention, accordingly, comprises the features of construction, combination of elements, and arrangements of parts which will be exemplified in the constructions hereinafter set forth and illustrated in the drawings.

For a fuller understanding of the nature and objects of the invention reference should be had to the following detailed description taken in connection with the accompanying drawings, in which:

FIGURE 1 is a schematic diagram of interconnected static elements illustrating a basic embodiment of this invention;

FIG. 2 is a schematic diagram of a transformer, rectifier and control circuit which may be used to provide power and logic signals to the annunciator of FIG. 1;

FIG. 3 is a block diagram indicating the logic functions of the static elements of FIG. 1 as connected to an indicator and an alarm;

FIG. 4 is a block diagram of a second embodiment of the invention;

2

FIG. 5 is a block diagram of a third embodiment of the invention;

FIG. 6 is a block diagram of a fourth embodiment of the invention;

FIG. 7 is a block diagram of a fifth embodiment of the invention; and

FIG. 8 is a schematic diagram of a static flasher comprised of static elements.

The annunciator systems in this application are illustrated by using static elements which include diodes and a plurality of saturable core static logic elements, which are different from each other in detailed structure, to provide different ones of the logic functions AND, OR, NOT and NOT-MEMORY. The various logic elements thus constructed are combined with each other and with various indicator devices to comprise annunciator systems which respond to abnormal conditions at a monitored point. The monitor may be a conventional trouble sensing device of the binary type such as a pressure switch, ratio switch, temperature switch, a limit switch of the magnetic or contact type, or a proximity switch, any one of which may open or close a contact in response to abnormal variations at the monitored point. Thus, the annunciator responds directly to the presence of a normally absent signal or to the absence of a normally present signal.

The following description is divided into two major parts. The first part is directed to the structure and operation of the different ones of the individual static saturable core logic elements. The second part is directed to the manner in which the logic elements may be interconnected with each other and combined with various indicator devices to perform the different annunciator functions in annunciator systems embodying this invention.

STATIC LOGIC ELEMENTS

The logic elements used in the annunciators disclosed are of the static type, since they give important advantages over the relays used in prior annunciators. The static logic elements shown and described herein are made up of all static parts such as diodes, magnetic cores and resistors. While these particular elements, and the specific arrangements thereof, are an important part of the specific aspects of the invention; it is to be understood that the broader aspects of the invention may be utilized through the use of other arrangements of these and/or other static parts.

The use of such static logic or decision elements gives many advantages such as: (1) there are no moving parts to wear and be replaced, (2) there are no contacts in the annunciator units to burn, stick or become dirty and fail to operate, (3) the power consumption is small, (4) operation is extremely fast with momentary application of a signal for as short a time as one cycle giving the required operation of the system, and (5) the annunciator is reliable in operation and requires substantially no maintenance.

Different nomenclature may be used for the various static logic or decision elements and their functions as used in the invention, and the names which have been chosen for use herein are as set forth below.

In the AND function, an output is obtained only when all of a given number of input signals are applied.

In the OR function, an output is obtained when any one of a number of inputs is applied.

In the NOT function, an output can be obtained only when no input signal is applied.

In the MEMORY function, sometimes called a FLIP-FLOP, an output occurs in response to an input, which output remains after termination of the input until the occurrence of a condition other than the change of the

input condition. A NOT-MEMORY is a memory comprised of a plurality of static NOT elements.

FIG. 1 of the drawing is directed to the body of one unit of an annunciator system embodying this invention for monitoring one point and includes schematic diagrams of typical OR elements OR 71 and OR 73, a NOT element N10, a two-input AND element A11, a NOT-MEMORY element NM12 and a two-input AND amplifier A13. Power is supplied to these elements from the power supply unit of FIG. 2.

The individual logic or decision elements will first be described, together with certain interconnections with each other and with the power supply unit, since an understanding of these elements will facilitate an understanding of the complete annunciator systems described in the second part hereof.

In FIG. 1 of the drawing, each terminal reference numeral ending in a given letter is connected to the output terminal of the power supply unit of FIG. 2 having a reference numeral ending in the same letter.

The two-input AND element A11 is comprised of a central saturable core 14 having a gate winding 15 and a reset winding 16. The reset circuit may be traced from terminal 52A, which is supplied with power from terminal 17A of the transformer (FIG. 2), through winding 16, rectifier 18, terminal 37, rectifier 19, input conductors 20, 21, 22 and 23, terminal 38, rectifier 24 to common 25B, common 26B (FIG. 2) and terminal 27B of the transformer. If this switching element A11 were a single input AND, no other reset circuit would be provided; however, another input conductor 30 of the two-input AND provides a second possible reset circuit for the reset current for winding 16. This second reset circuit may be traced from terminal 52A through winding 16, but now deviates through rectifier 28, terminal 39, rectifier 29, conductor 30 and input terminal 195L. An input signal may be applied to input terminal 195L by a connection from terminal 196L (FIG. 2) rectifier 197, rectifier 198 to common 199B.

The above-described apparent current flow in a reverse direction through rectifiers 19 and 24, for example, may occur because of the high voltage negative bias circuit through transformer terminals 27B, 26B, common 25B, rectifier 24, terminal 38, conductors 23, 22, 21 and 20, rectifier 19, terminal 37, resistor 40, terminal 41C, transformer terminals 42C and 43C. The negative bias current is maintained at a low level by resistor 40 but is always larger than the reset exciting current. Accordingly, the net current flow through rectifiers 24 and 19 is always in the forward direction. Thus, rectifiers 24 and 19 are forward biased rectifiers and therefore common 25B is always slightly positive with respect to terminal 37. As long as reset current does not exceed the current in the negative bias circuit, the principle of superposition is applicable in the same manner as it applies in known manner to a bilateral resistor. Accordingly, the reset current can in effect flow through rectifiers 19 and 24 in the reverse direction to accomplish reset of the core in the manner set forth above.

The above-identified high voltage negative bias circuit is also identified as a non-linear resistance circuit because the rectifiers 19 and 24 are reverse biased when a first input voltage larger than the reset voltage and having the same phase as the reset voltage is supplied through conductors 20, 21, 22, 23 and terminal 38 as an output from gate winding 44 of NOT-MEMORY element NM12, and when a second input voltage of the same character is applied through conductor 30. When such voltages are applied during a reset half cycle, terminal 37 and 39 are more positive than common and thus block the reset exciting current. The rectifier 24 is thus reverse biased. At the same time, the potential difference between input voltages, the reset supply voltage and the negative bias passes a current through resistors 40 and 52. Reference is made to the copending application of

Harley A. Perkins, Jr., Serial No. 640,006, filed February 13, 1957, which issued June 19, 1962 as U.S. Patent 3,040,242, for further explanation of the structure and operation of this non-linear resistance circuit.

The gating circuit for the AND element A11 may be traced from winding terminal 46D, which is energized from transformer terminal 45D, through winding 15, rectifiers 47 and 48, and common 49B and transformer common 26B to transformer terminal 27B. Rectifier 48 is the non-linear element for the gate winding and is structurally and operationally the same as the hereinbefore discussed non-linear devices. This non-linear resistance circuit may be traced from transformer terminal 27B, common 26B, common 49B, rectifier 48, resistance 50, terminal 51E and transformer terminals 52E and 53E.

When no input is present in either one of conductors 30 or 20, the core 14 traverses through its rectangular hysteresis loop each cycle. The previously described gating circuit drives the core 14 toward positive saturation when the gate voltage goes positive, the gate voltage being a sine wave. At the same time, the non-linear resistance circuit voltage across resistor 50 is going negative to cause a current to flow in the forward direction through rectifier 48 in the manner hereinbefore described. During the following half-cycle of the gate voltage, the rectifier 47 blocks the current flow attempting to drive the core towards negative saturation. At this time, the reset voltage, also a sine wave, is positive and drives the core toward negative saturation in the manner hereinbefore discussed. Simultaneously the non-linear circuit voltage across resistors 40 and 52 is going negative causing a current to flow in the forward direction through the non-linear resistance circuits. Thus, the core alternates between positive and negative saturation.

FIG. 2 is a schematic diagram of the power supply or transformer circuit, referred to in part in the above description of the reset and gating circuits, which may be used to provide the hereinbefore mentioned 180° out-of-phase relationship between the gate voltage and the reset voltage, and also provide the in-phase relationships between each of these voltages and its attending negative bias circuit. An alternating current source 53 is suitably connected to the primary winding 54. The secondary winding 55 is provided with seven taps, namely, end taps 53E and 43C, center tap 27B and intermediate taps 56F, 17A, 57G and 45D. Center tap 27B is used as common. When the 45D tap of the transformer is in the positive going half cycle of its full wave cycle with respect to common, said tap providing the gate voltage for winding 15, tap 17A is in its negative going half cycle of its full wave cycle with respect to common, said tap providing the reset voltage for winding 16. Similarly, the 43C tap acting in series with rectifier C provides a half-wave rectified negative bias for the non-linear element 48 in phase with the gate supply tap 45D while the 53E tap acting in series with rectifier E provides a half wave rectified negative bias for the non-linear elements in the reset circuit of the AND element A11 and in phase with the reset voltage from terminal 17A. It is obvious that the taps may be positioned to provide any desired voltages. Practical values which may be used are 57 volts RMS for each of the bias terminals 43C and 53E, 15 volts RMS for each of the gate supply terminals 45D and 56F, and 8 volts RMS for each of the reset terminals 17A and 57G, as referred to center tap 27B. To clarify the hereinbefore described phase relationships, the symbol θ indicates all points which have the same phase relationship at any time while the symbol ϕ represents all points which are 180° out of phase with the points θ at the same instant.

It is desirable that a plurality of these logic circuits be arranged so that the output of one provides the input for another. Such construction necessitates an in-phase

relationship between the gating circuit of the driving saturable core device and the reset circuit of the driven saturable core device to provide the previously discussed blocking action. The intermediate tap 56F is a gate supply voltage 180° out-of-phase with gate voltage supply tap 45D to provide opposed phase taps, to be selected at will, for proper connection for accomplishing this type of phasing relationship. Similarly, intermediate tap 57G is a reset voltage 180° out of phase with reset voltage supply tap 17A. The use of these additional taps in this respect for proper phasing between static elements will become apparent in the description of the annunciation systems hereinafter set forth.

In the two-input AND circuit A11 described hereinbefore, an output is produced by preventing reset of the core by blocking rectifiers 28 and 18 in the reset circuit thereof. This is done by feeding in a signal of the same phase and of greater amplitude than the reset voltage, through rectifiers 19 and 29. In this instance, 15 volts, the value of the gate supply voltage, is suitable as a blocking voltage. This blocking voltage prevents the reset voltage from accomplishing reset. Since the core 14 is thus already at positive saturation, it cannot support any positive voltage and will, therefore, gate an output when the gate voltage goes positive on the next half cycle. If either one of the rectifiers 18 or 28 are not blocked, reset of the core 14 can occur therethrough and no output will appear.

The two-input AND amplifier A13 is operationally identical with the hereinbefore described two-input AND circuit A11. Structurally, the AND element and the amplifier differ only in respect to minor changes such as the number of windings on the saturable core which can be changed to provide a higher output power. Other changes in structure and material to provide a higher power output will be obvious to one skilled in the art.

The two-input AND amplifier A13 is comprised of a saturable core 56, a reset winding 57 and a gate winding 58. The reset circuit may be traced from transformer 57G, reset terminal 58G, winding 57, rectifiers 58, 59 and 60, conductor 61, terminals 62 and 63, non-linear element 48, to common 49B and transformer terminals 26B and 27B. It may be noted that this circuitry provides for in-phase operation with respect to the gate circuit of AND element A11 serving as the driving circuit or input circuit through conductor 61 to the amplifier A13. The negative bias circuit for the reset circuit may be traced from transformer terminal 27B, common 26B, common 49B, rectifier or non-linear element 48, conductor 64, terminal 62, conductor 61, rectifiers 60 and 59, terminal 65, resistor 66, terminals 67 and 60E and transformer terminals 52E and 53E.

Rectifiers 60 and 69 are connected at terminal 70 so that either one or both may provide an output through rectifier 59 to block the reset voltage through rectifier 58. Accordingly, rectifiers 60, 69 and terminal 70 comprise an OR element OR71 which in turn constitutes one input of the two-input AND amplifier A13. The other input of the AND amplifier A13 is provided through rectifier 72, which in turn is connected to the output of an output of an OR element OR73 having an input through either of rectifier 74 or rectifier 75, which are connected to each other at terminal 76. Thus, an alternate reset circuit for winding 57 may be traced from transformer terminal 57G, winding terminal 58G, winding 57, terminal 77, rectifiers 78, 72 and 74, terminal 79, conductor 80, terminal 81, conductors 23, 22 and 21, terminal 82, conductor 83, terminal 84, rectifier 85, to common 86B and transformer common 26B and terminal 27B. The negative bias circuit may be traced from common 86B back through the previously traced reset traced reset circuit to rectifier 72, terminal 87, resistor 88, terminals 67 and 60E to transformer terminals 52E and 53E.

The gate circuit of the amplifier A13 may be traced

from transformer terminal 56F, winding terminal 89F, winding 58, rectifier 309, terminal 301, non-linear element 61, to common 62B, and transformer common 26B and terminal 27B. The negative bias circuit may be traced from transformer terminals 27B and common 26B to common 62B, non-linear element 61, terminal 60, resistor 89, terminal 90C and transformer terminals 42C and 43C.

The NOT circuit N10 differs from the two-input AND circuit A11 in that it has only one input and no reset supply voltage is provided for the core 91. The core 91 is then generally at positive saturation and an output occurs through terminal 94 and conductor 95 for each gating half-cycle. When an input is present through conductor 31 and rectifier 32, reset of core 91 occurs through terminal 96, reset winding 97, terminal 98, and the non-linear resistance circuit comprised of terminal 99E, resistance 100, non-linear element 101 and common 102B. The non-linear resistance circuit is connected appropriately across transformer common 26B and negative bias terminal 52E. The gating circuit may be traced from transformer terminal 56F, terminal 93F, gate winding 93, rectifier 103, terminal 94, non-linear element 35 and common 36B to transformer common 26B. The non-linear resistance circuit may be traced from transformer common 26B, common 36B, non-linear element 35, terminal 94, resistor 104, terminal 105C to transformer terminals 42C and 43C. In this NOT circuit N10, conductor 33 and rectifier 34 are ineffective and are included only because such structure becomes useful when two such NOT circuits are interconnected to form a NOT-MEMORY as at element NM12 as hereinafter described.

The NOT-MEMORY circuit MM12 is comprised of two NOT circuits N12H and N12K, each identical in structure and operation to the NOT circuit N10 as hereinbefore described. The NOT circuit N12H includes a core 106, an input-reset winding 107 and a gate winding 108. The input-reset circuit may be traced from positive input terminal 111, reset winding 107, then to a non-linear resistance circuit comprising a non-linear element 112 and resistor 113 connected through common 114B and terminal 115C to the transformer common 26B and terminal 42C respectively. The gate circuit may be traced from transformer terminal 45D, gate terminal 116, gate winding 108, rectifier 117, terminal 84, to common 86B through non-linear element 85. The non-linear resistance circuit also includes resistor 113 connected to terminal 119E, and transformer terminal 52E. When no input signal is present at terminal 111 to actuate reset coil 107, an output is gated to conductor 83.

The other NOT circuit N12K includes a saturable core 120, an input-reset winding 121 and a gate winding 44. The input-reset circuit may be traced through positive input terminal 122, reset winding 121, then to common 124B through non-linear element 123. The non-linear resistance circuit may be traced from transformer common 26B, and common 124B through non-linear element 123, resistor 125 to terminal 126E and transformer terminal 52E. The gate circuit may be traced from transformer terminal 56F to gate terminal 127F, gate winding 44, rectifier 128, terminal 38, non-linear element 24 to common 25B and transformer common 26B. The non-linear resistance circuit may be traced from common 25B, non-linear element 24, terminal 38, resistor 129, terminal 130C to transformer terminal 42C. When no input signal is present at terminal 122 to actuate reset winding 121, an output is gated through gate winding 44, rectifier 128, and terminal 38 to conductor 131.

The NOT circuits N12H and N12K are interconnected to form the NOT-MEMORY circuit NM12. The output of each NOT circuit is connected to the input of the other. Thus, output conductor 131 of NOT circuit N12K is connected to input terminal 111 of NOT circuit N12H through terminal 81, conductor 23, terminal 132, con-

ductor 22, terminal 133, conductor 134, and rectifier 135. The output conductor 83 of NOT circuit N12H is connected to the input terminal 122 of NOT circuit N12K through terminal 82, conductors 21 and 22, terminal 132, conductor 136 and rectifier 137.

The input terminal 111 also serves as an output terminal of OR element OR 138 comprised of input rectifiers 110 and 135. Similarly, the input terminal 122 also serves as an output terminal of OR element OR 139 comprised of rectifiers 137 and 140. Rectifiers 140 and 119 are connected to inputs external of the NOT-MEMORY system.

In the operation of the NOT-MEMORY circuit, if no input signal is present through rectifier 110 to the reset winding 107, core 106 is not reset and thus a half-cycle later the gate circuit including winding 108 gates an output through the conductors 83, 21, 22, 23 and 136 to rectifier 137 and reset winding 121 of NOT circuit N12K to thus reset core 120. A half-cycle later, the gate circuit of NOT circuit N12K including winding 44 does not gate an output through rectifier 128, and conductors 131, 23, 22, and 134. Thus NOT circuit N12H has no input and therefore has an output to again reset core 121 in NOT circuit N12K. This stable condition is therefore self-sustaining. The output is a half-wave voltage in phase with the gate voltage to winding 108 of NOT circuit N12H. This output appears externally of the NOT-MEMORY circuit through terminal 82 to conductor 20, and through terminal 81, to conductors 80, 146 and 147. If an input voltage is now applied through rectifier 110 to reset winding 107 of NOT circuit N12H, core 106 will reset. A half-cycle later no output appears from NOT circuit N12H across conductors 83, 21, 22 and 136 to the input-reset winding of NOT circuit N12K and thus core 120 is not reset. A half-cycle later, NOT circuit N12K gates a second output through winding 44 and rectifier 128 to conductor 131, which second output is opposite in phase to the first output. The second output appears externally of the NOT-MEMORY circuit through terminal 81 to conductors 80 and 141, and through conductors 23, 22 and 21 to terminal 82 and then to external conductor 20. This second output also resets core 106 of NOT circuit N12H through conductors 131, 23, 22, 134, rectifier 135 and input-reset winding 107 so that NOT circuit N12H will have no output on its gating half-cycle. Even though the input is removed, the output remains stably in this condition. The output may be shifted back to the original phase by presenting an input voltage to NOT circuit N12K through conductor 142 and rectifier 140 of the OR element OR139. It is to be noted that normally the NOT-MEMORY has an output of either one phase or the other. However, only one of these outputs will be effective with respect to any other static element to be driven thereby. If input voltages are applied at both inputs, that is, through rectifier 140 and rectifier 110, both of cores 106 and 120 will be reset resulting in zero output for both phases. Thus, it is seen that storage of information in the NOT-MEMORY will remain indefinitely as long as no signal is applied to change the state.

ANNUNCIATOR SYSTEMS

The plurality of saturable core switching devices hereinbefore described are interconnected with each other and combined with various indicator devices to comprise annunciators embodying this invention as shown in FIGS. 3 through 7. Each of these annunciators to be described hereinafter is comprised of an alarm or audible indicator system, a light or visual indicator system and an acknowledge system. These individual systems differ in detail from one annunciator to another, but the basic cooperation between systems is common to all disclosed annunciators and follows the operation pattern of Chart I.

8
Chart I

State	Sensing Device	Visual Indicator	Audio Alarm	Acknowledge
1.....	Normal.....	Dim.....	Off.....	Off.....
2.....	Abnormal.....	Flashing.....	On.....	Off.....
3.....	Abnormal.....	Steady bright.....	Off.....	On Momentarily.....
4.....	Normal.....	Dim.....	Off.....	Off.....

Normal states 1 and 4 are the same thus indicating that the annunciator system returns to normal when the sensing device return to normal. Accordingly, the annunciator system may go directly from state 2 to state 4, omitting state 3, when the abnormal condition is corrected before the acknowledge signal is provided.

In addition to the primary function of the annunciator to actuate an alarm and visual indicators, it may be desirable that other signals be generated that can be used in another control system to cause automatic shut-down or corrective procedure. These features will be more fully explained hereinafter.

FIG. 1 discloses one mode of interconnecting the various static logic elements to provide the annunciator functions set forth in Chart I. FIG. 3 is a symbolic diagram of the system of FIG. 1 showing the same interconnections between the logic elements, but showing the logic elements in symbolic form, and additionally showing the various indicator devices combined therewith to provide the desired annunciator signals.

The annunciator system of FIG. 1 and FIG. 3 is constructed to respond to an abnormal condition as indicated by the presence of a normally absent signal and may be driven by direct current or full wave rectified direct current of a proper voltage and phasing to provide a proper input for the static logic circuits hereinbefore described.

Referring to FIG. 3, the output through normally open contact 143 of a trouble sensing device (not shown) is connected to the input of NOT element N10 through conductor 31 which contact when closed provides NOT element N10 with a signal from terminal 196L of transformer-rectifier direct current source 200 (shown in detail in FIG. 2). The output of terminal 196L is also connected at terminal 195L to one input of AND element A11 through conductor 30. The output of NOT element N10 is connected to a conductor 146 providing a signal to other equipment (not shown) when a signal from the sensing device is not present, and could be used to automatically start or stop such other equipment as may be desired. The output of NOT element N10 also is connected to one input of NOT-MEMORY element NM12 through conductor 95. An acknowledge switch 144 is connected to the other input of NOT-MEMORY element NM12 through conductor 142, which switch when closed provides NOT-MEMORY element NM12 with a signal from terminal 292 of transformer-rectifier direct current source 201 (FIG. 2). One output of the NOT-MEMORY element NM12 is connected to the other input of AND element A11 through conductor 20. The AND element A11 output is connected through conductors 64 and 145 and through OR element OR154 to drive a horn amplifier and a horn. The A11 output is also connected to one input of OR element OR71 through conductors 64 and 61. The second output of the NOT-MEMORY element NM12 is connected to a shut down element (not shown) for other equipment through conductors 141. The second NOT-MEMORY output is also connected first to the second input of OR element OR71 through conductors 80 and 147 and, second, to the first input of OR element OR73 through conductors 80 and 148. The second input 210 of OR element OR73 is connected to the output from flasher unit 221 for providing an output to the other input of the AND amplifier A13 through conductor 150. The AND amplifier A13 output is connected to actuate an indicator such as a lamp L through conductor 151. The lamp is connected in series circuit relationship with a resistor

152. A suitable direct current source of power, such as may be supplied by taps 45D and 56F of the transformer of FIG. 2 through rectifiers 203 and 204 respectively, is connected to resistor 152 and across the lamp to common to provide the dimly lit visual signal of the normal state hereinbefore described. It is obvious that the voltage value and resistor value may be adjusted to provide any desired degree of contrast between the dimly lit condition and the steady bright condition. The normal dimly lit condition of the lamps eliminates the necessity of periodically testing the lamps.

When an abnormal condition occurs at the monitored point in the annunciator of FIG. 3, contact 143 closes to provide a signal of proper voltage and phase to the input of the annunciator. A practical voltage of 15 volts may be provided through a step-down transformer and rectifier 209 (FIG. 2) having a primary coil energized by the alternating current source 53 of FIG. 2. This signal provides an input to NOT element N10 which then gates no output to the NOT-MEMORY element NM12. The removal of the NOT-MEMORY input in this manner does not effect its output because of the hereinbefore described memory feature and accordingly the NOT-MEMORY continues to gate an output of proper phase to one input of the AND element A11. The closed contact 143 also provides an input signal to the other input of the AND element A11. Thus, the AND element A11 gates an output to sound the horn. The AND output also drives an input of the two-input AND amplifier A13 through the OR element OR71. The flasher 221 provides a periodic output to the other input of the two-input AND amplifier A13 through the OR element OR73. The last two mentioned inputs cooperate to provide a periodic output from the AND amplifier A13 to flash the light.

It is a very desirable feature of the invention that the flasher 221 is connected into the circuit of the lamp on the input side of the amplifier A13. This makes it possible to use a flasher of low-energy output, which is small and compact and still use a single flasher for supplying a substantial number of annunciator points as is described hereinafter. This advantageous result is obtained because the flasher does not have to supply the energy for lighting the lamps, since this energy is supplied to the amplifier A13 (referring to FIG. 1) at the terminal 89F of the gate winding 58, from the terminal 56F of the power supply unit, shown in FIG. 2. There is further advantage in the use of a flasher composed of static elements, as shown in FIG. 8, since there are no moving parts to wear or stick, and there are no contacts or moving commutators, which are likely to wear and burn due to arcing, particularly if the flasher has to interrupt the power required to light the lamp or lamps.

These advantages of the flasher arrangement are illustrated by considering, for example, one practical embodiment of the invention where each lamp requires 350 milliamperes at 4 volts half-wave direct current, so that the flasher would have to handle 3500 milliamperes, if 10 lamps might be lighted simultaneously and flashed directly by the flasher. By having the flasher connected at the input side of the AND amplifier A13, the current required of the flasher for each point is only 6 ma.; or 60 ma. if the lights at ten points might have to be flashed, compared with the current of 3500 ma. which would otherwise be required for the ten points. This makes possible the use of a small low cost flasher which uses only static parts. By providing an individual AND amplifier A13 for the light for each point, each amplifier need have an output of only 350 ma. and may also be of low-cost static parts and of the type which is frequently used as a preamplifier at the input of a larger amplifier; which is not required in the lamp circuits of the arrangements described herein.

If, when the audio alarm is sounded and the light is flashing, the operator temporarily closes the acknowledge switch 144, an input signal is provided to the other terminal of the NOT-MEMORY element NM12 causing it to

gate an output having a phase opposite to that of its first mentioned output. This change in output phasing is equivalent to no input for the one input of the AND element A11 since the driving voltage from the NOT-MEMORY and the reset voltage of the AND element are no longer in phase. Thus, the AND element A11 gates no output and the horn is silenced. The aforementioned change in NOT-MEMORY output phasing now provides a driving input for the AND amplifier A13 through OR71 and also through OR73 to provide both inputs of the AND amplifier A13 with a steady signal. Accordingly, the AND amplifier A13 gates a continuous output which causes the lamp to assume a steady bright condition.

15 When the abnormal condition is eliminated, contact 143 opens to terminate an input signal to the AND element A11 and to the NOT element N10. The NOT element N10 thus gates an output to the first mentioned NOT-MEMORY input causing the NOT-MEMORY output to reassume its initial phasing to provide a driving input for one input of the AND element A11. The same phase change occurs simultaneously in the NOT-MEMORY output leading to the AND amplifier A13; however, this output is now out-of-phase with the AND amplifier reset voltage and thus effectively constitutes no input for the AND amplifier A13. The AND amplifier A13 gates no output to thus terminate an output to the light. The lamp L now glows dimly in the circuit including resistor 152.

20 30 It is obvious that if the abnormal condition is terminated before the acknowledge switch is closed, the signal to the one input of the AND element A11 is interrupted, thus terminating the AND output to silence the horn and also to terminate the input through OR71 to the AND amplifier A13 to thus permit the lamp to glow dimly again.

35 Thus far there has been described an annunciator for monitoring a single point to indicate a change in condition indicated by closing of the switch 143, and it will be understood that in most annunciator systems there will be a plurality of monitored points indicated in FIG. 3 by the additional switches 143' and 143''. There will then be connected to each additional input terminal 195L' and 195L'' a duplicate of the circuit previously described (indicated by the box of dot and dash lines) each including the elements N10, A11, NM12, OR71, OR73, A13 and lamp L. Thus it may be determined from the lighting of one or more of the plurality of lamps L, L' and L'' which of the respective signal initiating devices 143, 143' and 143'' has been actuated.

40 45 50 However, there need be only one audible alarm such as a horn bell or buzzer common to all of the monitored points. This one alarm and its associated amplifier is connected to the circuit for each monitored point through the common OR element OR154 which has as many inputs 145, 145' and 145'' as there are monitored points, so that the actuation of any signal initiation switch 143, 143' or 143'' will cause the one audible alarm to sound.

55 60 65 As previously pointed out there may be only one flasher unit 221 common to all or a group of the monitored points, since it is connected through a flasher bus 212 to the flasher inputs 210, 210' and 210'' of the respective circuits for the different points. Furthermore, there is only a single acknowledge or audio silence switch 144 for all, or a group of the monitored points. Conductor 155 provides for connecting the single audio silence switch 144 in common with all such plural annunciators. It should be noted that closing the switch 144 when the system is in a normal condition has no effect since both inputs to the NOT-MEMORY would thus be provided with signals to reset both NOT elements of the NOT-MEMORY, in which event there arises a no-output condition.

70 75 In FIGS. 4 through 7 there are disclosed block diagrams of modified annunciators. For purposes of simpli-

fication, each system is shown as monitoring a single point, but it will be understood that the equipment individual to each point will be duplicated for other points and that a single horn circuit, a single flasher and a single reset or acknowledgement switch may be used in common to all, or a group, of the monitored points, as shown and described in detail in connection with FIG. 3.

Referring now to FIG. 4, there is disclosed a symbolic diagram of an annunciator having static logic elements of the same type as disclosed in FIG. 1. The static logic elements are interconnected in a different fashion but cooperate to perform the same functions as that of the FIG. 1 annunciator. In addition, the annunciator of FIG. 4 differs from that of FIGS. 1 and 3 in that it is adapted to respond to the absence of a normally present signal. It will be obvious to one skilled in the art how the static logic elements of the type shown in FIG. 1 may be interconnected in the manner illustrated in FIG. 4 and described in the following matter relating thereto.

In the annunciator system of FIG. 4, a trouble sensing device (not shown) operates to open normally closed contact 156 to terminate the input signal to NOT element N157 through the OR element OR158, thus causing NOT element N157 to gate an output to the horn amplifier and horn to thus sound the audio indicator. The NOT element N157 output also drives a two-input AND element A159 in cooperation with the flasher output provided at the other input of the AND element AND A159. AND amplifier A160 then gates a periodic output to change the lamp signal from a steady dim condition to a flashing bright condition. The termination of the input to the NOT-MEMORY element NM161 has no effect upon its output, therefore, it continues to effectively gate no output with respect to the NOT element NOT N157 and the AND amplifier A160. If the operator now closes acknowledge switch 162, NOT-MEMORY element NM161 gates an effective output through the OR element OR158 to cause the NOT element NOT N157 to terminate its output to the audio system thus silencing the horn. At the same time, the NOT-MEMORY element NM161 output changes the lamp condition from one of flashing bright to one of steady bright through the OR element OR164 and amplifier A160. Elimination of the abnormal condition closes the contact 156 to restore an input signal to the NOT-MEMORY element NM161 and the NOT element N157. The NOT-MEMORY element NM161 then returns to its previous condition of no effective output thus eliminating an input to the preamplifier A160 and permitting the lamp to return to its steady dim condition in its circuit including resistor 163. NOT element N157 then gates no output and thus permits the audio signal to remain in a silenced condition. At the same time, the no output condition of NOT element N157 provides no input at one terminal of the AND element A159, thus prohibiting AND element 159 from gating an output to drive preamplifier A160. The light remains in a dim condition. Conductor 204 provides a shutdown signal, if desired.

The acknowledge switch 162 and the audio indicator may be connected in common with a plurality of annunciators in the same manner as disclosed in FIG. 3. It is obvious that if an abnormal condition is eliminated before the acknowledge switch is closed, the hereinbefore described operations of the static logic elements causing a change in signal from steady dim to flashing bright are reversed and the annunciator again assumes a normal condition.

Referring now to FIG. 5, there is disclosed in block diagram, a further embodiment of the invention in an annunciator having the same type of static logic elements described in detail with respect to FIG. 1. The logic elements are interconnected in a manner not hereinbefore described, but cooperate with each other to perform the same annunciator functions as the foregoing annunciator systems. This annunciator responds to an abnormal con-

dition as indicated by the absence of a normally present signal.

In the annunciator system of FIG. 5, a trouble sensing device (not shown) operates to open a normally closed contact 165 to thus terminate an input signal through the OR element OR166 to NOT element N167 thus causing it to gate an output to actuate the horn amplifier and horn. NOT element N167 also provides an input to AND element A163 which gates an output to one input of the two-input AND preamplifier A169 through the OR element OR170. The flasher provides a periodic input to the other input of the AND preamplifier A169 through the OR element OR171 which cooperates with the first mentioned AND preamplifier input to cause the preamplifier to gate an output to periodically energize the lamp to thus provide the flashing bright condition. The absence of the normally present annunciator input signal has no effect on the NOT-MEMORY element NM172 which continues to gate an ineffective output with respect to NOT element N167. If the operator now closes acknowledge switch 173, NOT-MEMORY element NM172 now is actuated to its opposite gating condition and now gates an effective output to NOT element N167 causing it to gate no output to thus terminate the signal to one input of the AND amplifier A169. The lack of a NOT element N167 output likewise terminates the signal to the audio signal system thus silencing the horn. The same NOT-MEMORY output also now provides a steady effective signal to both inputs of the AND amplifier A169 through each of the elements OR170 and OR171. AND amplifier 169 now gates a steady output causing the lamp to assume a steady bright condition. Elimination of the abnormal condition causes the sensing device to reclose switch 165, in which event an input signal is reapplied to the opposite terminal of NOT-MEMORY element NM172 reversing its output condition thus producing an ineffective output with respect to NOT element N167 and with respect to the two inputs of amplifier A169. The reclosed switch also provides an input through the OR element OR166 to NOT element N167 which now gates no output to either audio or visual signal. The lamp now glows dimly in its circuit including resistor 174. If the abnormal condition should be corrected before the acknowledge switch is closed, it is obvious that the hereinbefore described operations of the static logic elements causing a change from a dimly glowing visual condition to a flashing bright condition combined with sounding audio alarm are reversed. Conductor 205 provides a shutdown signal if desired.

The indicator silence switch 173 and the audio system may be connected in common with a plurality of annunciators in the same manner as disclosed in FIG. 3.

Referring now to FIG. 6, there is disclosed in block diagram a further embodiment of the invention in an annunciator having the same type of static logic elements described in detail with respect to FIG. 1. The logic elements are interconnected in a manner not hereinbefore described, but cooperate with each other to perform the same annunciator functions as the foregoing annunciator systems. This annunciator responds to an abnormal condition as indicated by the presence of a normally absent signal. In addition, the annunciator of FIG. 6 may respond to an annunciator input signal consisting of direct current, alternating current, one-half wave direct current or full wave direct current as desired.

In the annunciator system of FIG. 6, a trouble sensing device (not shown) operates to close a normally open contact 175 to provide an annunciator input signal in a first direction to NOT element N176 and in a second direction through the OR element OR177 to one input of the two-input AND amplifier A178. As a result, NOT element N176 ceases gating an output through the OR element OR179 to one of the plural inputs of AND element A195. The remaining two inputs of AND element A195, shown unconnected to other devices, lead

from the outputs of similarly arranged OR elements in other annunciator systems (not shown) of the same type as the annunciator now described, wherein an abnormal condition at the monitored point provides a signal through the respective OR elements as through the OR element OR179 as above described. Conversely a normal condition will provide no signal through the OR element OR179. Therefore, when conditions at all monitored points are normal, AND element A195 gates an output to NOT element N180 which responds to gate no output to the horn amplifier to maintain the horn in a silenced condition. An abnormal condition causes NOT element N176 to gate no output causing AND element A195 to gate no output to NOT element N180. NOT element N180 then gates an output to actuate the horn amplifier to sound the horn. It is seen that an abnormal condition at any monitored point terminates an output from AND element A195, common to all annunciators, to sound the common audio indicator. Conductor 196 may be provided to lead directly to other annunciators to connect the audio indicator silence switch in common with all annunciators. NOT element N176 also ceases gating an output to NOT-MEMORY element NM181; however, the absence of an input signal to NOT-MEMORY element NM181 has no effect on NOT-MEMORY element NM181 which continues to gate an ineffective output to AND element A182 and to the two input terminals of the two-input AND amplifier A178 through the OR elements OR177 and OR183. The annunciator input signal provided through contact 175, provides an input signal to one input of the AND amplifier A178 through the OR element OR177, which input cooperates with the periodic input to the other AND amplifier input provided by the flasher unit to cause the AND amplifier A178 to gate a periodic output causing previously dimly glowing lamp to assume a flashing bright condition. If the operator now closes acknowledge switch 184, an input signal is provided at the other input of NOT-MEMORY element NM181 which then reverses its output condition to now gate an effective output to both inputs of the two-input AND amplifier A178 through the OR elements OR177 and OR183 to provide a steady output which changes the lamp condition from flashing bright to steady bright. Simultaneously, NOT-MEMORY element NM181 gates an effective output to AND element A182 which gates an output through the OR elements OR179 and A195 to NOT element N180. NOT element N180 now ceases to gate an output and thus the audio alarm is silenced. When the abnormal condition is eliminated, contact 175 opens to terminate the input signal to NOT element N176 which then gates an output through the OR element OR179 to provide an input for NOT element N180 which in turn is prevented from gating an output to sound the audio system. The output from NOT element N176 provides an input to the opposite input of NOT-MEMORY element NM181 which reverses its output condition to gate an ineffective output with respect to AND amplifier A178 and AND element A182. The termination of the annunciator input signal likewise interrupts the input through the OR element OR177 to one input of the AND amplifier A178 thus preventing the AND amplifier from gating an output to the lamp signal system. If the abnormal condition should be eliminated before the acknowledge switch is closed, it is obvious that the operations of the static logic elements which change the condition of the lamp from one of dim glow to one of flashing bright are reversed. Conductor 206 provides a shutdown signal, if desired.

Referring now to FIG. 7, there is disclosed in block diagram a further embodiment of the invention in an annunciator having the same type of static logic elements described in detail with regard to FIG. 1. The logic elements are interconnected in a manner not hereinbefore described, but cooperate with each other to perform the

same annunciator functions as the foregoing annunciator systems. This annunciator responds to an abnormal condition as indicated by the absence of a normally present signal. In addition, the annunciator of FIG. 7 responds to either direct current or full-wave direct current provided through contact 185 of the trouble sensing device (not shown). In the annunciator of FIG. 7, a trouble sensing device (not shown) responds to an abnormal condition to open 10 normally closed contact 185 to thus terminate the annunciator input signal to one input of NOT-MEMORY element NM186 which is unaffected by the interruption of its input signal and therefore continues to gate an ineffective output. The aforementioned termination of the annunciator input signal through contact 185 provides no input through the OR element OR188 to NOT element N187 to cause NOT element N187 to thus gate an output which actuates the horn amplifier and sounds the horn. The aforementioned termination of the input signal 20 through contact 185 performs a third action in terminating the input through the OR element OR189 to NOT element N190 thus causing NOT element N190 to gate an output through the OR element OR191 to provide an input to the one input AND amplifier A192 which gates an output to actuate the lamp. At the same time, the flasher is providing a periodic input to NOT element N190 which now gates a periodic output through the OR element OR191 to AND element A192 to cause the lamp condition to change from a steady dim condition to a 30 flashing bright condition. If the operator now closes the acknowledge switch 193, an input is provided to the other terminal of NOT-MEMORY element NM186 which causes it to now gate an effective output in a first direction through the OR element OR191 to AND element A192 causing an output which provides a steady bright lamp condition, and in a second direction through the OR element OR188 to provide an input for NOT element N187 which then gates no output to thus deactivate the horn amplifier and silence the horn. When the abnormal 40 condition is eliminated, the sensing device closes its contact 185 which provides an annunciator input in a first direction to the other input of NOT-MEMORY element NM186 causing it to reverse its output condition to gate an ineffective input with respect to AND element A192 amplifier to tend to terminate the steady bright lamp condition and with respect to NOT element N187 tending to cause it to gate an output to sound the horn. The annunciator input takes a second direction through the OR element OR189 to NOT element N190 causing NOT 50 element N190 to gate no output through the OR element OR191 to AND element A192 thus permitting the lamp to return to its normal dim condition in its circuit including resistor 194. The flasher is ineffective since NOT element N190 is now provided with a steady input. The 55 annunciator input takes a third direction through the OR element OR188 to NOT element N187 causing a no-output condition to deactivate the horn amplifier and silence the horn. If the abnormal condition should be eliminated before the acknowledge switch is closed, it is obvious that the operations of the static logic elements causing the lamp to change condition from dim to flashing bright and causing the audio system to change from a silenced condition to an audible condition, are reversed to cause the annunciator system to reassume a normal 60 condition. Conductor 207 provides a shutdown signal, if desired.

A plurality of annunciators of the type shown in FIG. 7 may be connected in common with audio silence switch 193 and the audio indicator in the same manner as disclosed in FIG. 6.

FLASHER

The flasher 221 disclosed in FIG. 8 provides the pulsating signal to the lamp preamplifier in the manner hereinbefore described and is comprised of a static element oscil-

lator stage 222 and a static element buffer stage 223. The oscillator stage 222 is comprised of two static magnetic NOT elements N224 and N225 interconnected with each other and a pair of resistor-capacitor circuits to provide regenerative feedback to sustain oscillation. The buffer stage 223 is comprised of two static magnetic INHIBITED-NOT elements IN273 and IN275 interconnected with each other and connected to the oscillator to provide high output power, to isolate the oscillator from its load, and to provide a fast switching action.

In the oscillator stage 222, the first NOT element N224 is comprised of a magnetic core 226 having a gating winding 227 which may be energized from transformer terminal 56F (FIG. 2) which may be connected to flasher terminal 228 Ga, conductor 229, winding 227, rectifier 230, rectifier 231 of non-linear impedance 232, common conductor 233 and flasher terminal 234 Ca which may be connected to transformer common terminal 26B. The non-linear impedance includes transformer terminal 52E, flasher terminal 235 Gb, conductors 236 and 236a rectifier 237, rectifier 231, conductor 233, terminal 234 Ca, and transformer terminal 26B. Rectifier 230 and non-linear impedance 232 connect gate winding 227 to output terminal 240. The NOT reset winding 228 is connected to a NOT input terminal 238 in circuit with a rectifier 239, rectifier 241 of non-linear impedance 242, conductor 233, terminal 234 Ca, and transformer 26B. Thus winding 228 is energized in response to a positive signal applied to NOT input terminal 238. The non-linear impedance includes transformer terminal 26B, flasher terminal 234 Ca, conductor 233, rectifier 241, resistor 311, conductor 229, flasher terminal 228 Ga and transformer terminal 26B.

The NOT element N225 of oscillator 222 is comprised of a magnetic core 312 having a gating winding 243 which may be energized from transformer terminal 45D, through flasher terminal 235 Gb conductor 236, winding 243, rectifier 244, rectifier 245 of non-linear impedance 246, common conductor 233a, flasher terminal 234 Ca and transformer terminal 26B. The non-linear impedance 246 includes transformer terminal 26B, flasher terminal 234 Ca, conductor 233a, rectifier 245, resistor 247, conductors 229a and 229, flasher terminal 228 Ga and transformer terminal 42C. Rectifier 244 and impedance 246 connect gate winding 243 to output terminal 253. The magnetic core 312 is also provided with a NOT reset winding 247 connected to NOT input terminal 248, rectifier 249, rectifier 251 of non-linear impedance 250, conductor 233a, flasher terminal 234 Ca, and transformer terminal 26B. Thus reset winding 247 is connected to respond to a positive input, applied at NOT input terminal 248. The non-linear impedance 250 includes transformer terminal 26B, flasher terminal 234 Ca, conductor 233a, rectifier 251, resistor 252, conductor 236, terminal 235 Gb and transformer terminal 45D.

The output terminal 240 of NOT element N224 is connected through a capacitor 254 to the NOT input 248 of NOT element N225. The capacitor 254 is also connected in circuit with a resistor 255 and rectifiers 256 and 259 which complete a hereinafter described discharge circuit for capacitor 254. Similarly, the output terminal 253 of NOT element N225 is connected through a capacitor 257 to the NOT input 238 of NOT element N224. Capacitor 257 is also connected in circuit with a resistor 258 and rectifiers 259 and 256 which complete a hereinafter described discharge circuit for capacitor 257. The output terminal 240 of NOT element N224 and the output terminal 253 of NOT element 224 are each connected to an input of the buffer stage 223 in a manner hereinafter described.

In the buffer stage 223, the first static INHIBITED-NOT element IN273 is comprised of a magnetic core 260 having a gate winding 261 and a reset winding 262. The gate winding 261 may be energized from trans-

former terminal 45D, through flasher terminal 235 Gb, conductors 236 and 236a, winding 261, rectifier 263, rectifier 264 of non-linear impedance 265, conductor 233, flasher terminal 234 Ca to transformer terminal 26B. The non-linear impedance 265 includes transformer terminal 26B, flasher terminal 234 Ca, conductor 233, rectifier 264, resistor 266, conductor 229, flasher terminal 228 Ga and transformer terminal 56F. Rectifier 263 and non-linear impedance 265 connect gate winding 261 to output terminal 267. The reset winding is connected to NOT input terminal 268 through rectifier 269, reset winding 262, INHIBIT input terminal 270, rectifier 271 of non-linear impedance 272, conductor 233, flasher terminal 234 Ca to transformer terminal 26B. The non-linear impedance 272 includes transformer terminal 26B, flasher terminal 234 Ca, conductor 233, rectifier 271, resistor 274, conductors 236a and 236, flasher terminal 235 Gb and transformer terminal 45D.

The other INHIBITED-NOT element IN275 is comprised of a magnetic core 276, a gate winding 277 and a reset winding 278. The gate winding 277 is energized from transformer terminal 56F, flasher terminal 228 Ga, conductors 229 and 229a, winding 277, rectifier 279, rectifier 280 of non-linear impedance 281, conductor 233a, flasher terminal 234 Ca, to transformer terminal 26B. The non-linear impedance includes transformer terminal 26B, flasher terminal 234 Ca, conductor 233a, rectifier 280, resistor 282, conductor 236, flasher terminal 235 and transformer terminal 45D. The rectifier 279 and non-linear impedance 281 connect gate winding 277 to output terminal 267. The reset winding 278 is connected to NOT input terminal 268 through rectifier 283, and is connected through INHIBIT input terminal 284, rectifier 285 of non-linear impedance 286, conductor 233a, and terminal 234 Ca to transformer terminal 26B. The non-linear impedance 286 includes transformer terminal 26B, flasher terminal 234 Ca, conductor 233a, rectifier 285, resistor 289, conductors 229a and 229, flasher terminal 228 and transformer terminal 56F.

The output terminal 240 of the oscillator 222 is connected through rectifier 287 to the INHIBIT input terminal 270 of the buffer stage 223. Similarly, the output terminal 253 of the oscillator 222 is connected through rectifier 288 to the INHIBIT input terminal of the buffer stage 223.

In describing the operation of the flasher 221 as hereinbefore described, it is assumed that as a prime condition, NOT element N224 is gating an output signal through output terminal 240 to NOT element N225 to reset its core 312 to thus prevent an output from being gated through output terminal 253. The output through terminal 240 also charges capacitor 254 with a charging current which is determined by the coercive force of the core 312, the resistor 252 and the winding 247. As capacitor 254 continues to be charged with each additional gating pulse through terminal 240, the other capacitor 257 is discharging through output terminal 253, rectifier 283, resistors 247 and 259, conductors 229a and 229, rectifier 259 and resistor 258 back to the capacitor 257. Additionally, capacitor 257 may discharge through rectifier 256 through the transformer windings connected across terminals 228 Ga and 234 Ca. The NOT element N224 thus receives no effective input to reset its core 226 and accordingly continues to gate an output to capacitor 254. As capacitor 254 continues to charge, it eventually blocks the reset signal to NOT input terminal 243 and at the same time reduces its own charging rate. The termination of the NOT input to reset winding 247 causes NOT element N225 to begin gating an output through its output terminal 253 to begin charging capacitor 257 and to cause reset of core 226 through NOT input terminal 238. The NOT element N224 now ceases gating an output through 240, thus permitting charged capacitor 254 to discharge through terminal 240, rectifier 287, resistors 237 and 274, con-

ductors 236a and 236, rectifier 256 and resistor 255 back to capacitor 254. Additionally, capacitor 254 may discharge through rectifier 259 through terminals 228Ga and 235Gb connected across the transformer. The NOT element N225 thus receives no effective input to reset its core and accordingly continues to gate an output to reset core 226 of NOT element N224 and to continue charging capacitor 257. As capacitor 257 continues to charge, it eventually blocks the reset signal to NOT input terminal 238 and at the same time reduces its own charging rate. The NOT element N224 begins gating an output to begin a new cycle of operation and thus the NOT elements N224 and N225 cooperate to provide the desired oscillations.

As the NOT element N224 is gating an output signal through terminal 240 to charge its associated capacitor 254 and reset core 312 of NOT element N225, all in the manner hereinbefore described, the output through terminal 240 also is providing a signal through rectifier 287 to INHIBIT terminal 270 of INHIBITED-NOT element IN273 in the buffer stage 223. This INHIBIT input voltage signal is the same phase and opposite in direction to the reset voltage across reset winding 262. This input signal 270 increases as capacitor 257 charges to prevent full reset of core 226. When the INHIBIT signal reaches a predetermined level reset of core 260 is blocked causing it to gate an output through terminal 265, 267 and flasher output terminal 290. The output signal from the INHIBITED-NOT element IN273 is provided through NOT input terminal 268 and rectifier 283 to reset winding 278 of INHIBITED-NOT element IN275 to thus reset core 276 which prevents gating winding 277 from gating an output through rectifier 279 to output terminal 267 and flasher output 290. The INHIBITED-NOT element IN273 continues gating an output to flasher terminal 290 so long as the NOT element N224 of the oscillator stage 222 is gating an output. While NOT element N224 is gating an output, capacitor 257 is discharging to provide a signal through output terminal 253 and rectifier 288 to INHIBIT input terminal 284 in the manner previously described. But, the NOT input signal is not blocked, as the voltage level on the capacitor is too low at this time and thus the capacitor 257 discharge signal to INHIBIT terminal 284 is insufficient to inhibit INHIBITED-NOT element IN275. In a similar fashion, when NOT element N225 is gating an output signal to charge capacitor 257 and reset the NOT element N224 in the manner previously described, the output signal from N225 through output terminal 253 is providing an input signal through rectifier 288 to INHIBIT terminal 284 of INHIBITED-NOT element IN275. This INHIBIT signal opposes the NOT signal to reset winding 278, thus blocking reset of core 276 which then gates an output through rectifier 279, and output terminal 267 to flasher output terminal 290. At the same time, the output from IN275 provides a signal through NOT terminal 269 to reset winding 262 causing reset of core 260 to thus terminate its output signal to flasher output terminal 290.

Thus, it is seen that the buffer stage 223 responds to oscillations of the oscillator stage 222 to alternately provide signals of opposite phase to the flasher output terminal 290. Accordingly, if the output terminal 290 is connected to an input terminal of a static element such as preamplifier A13 of FIG. 3 or any of the preamplifiers as hereinbefore described, the output signal from 290 will periodically be in phase with the reset voltage of said static element thus providing a pulsing "on" input signal.

The above described static flasher is disclosed and claimed in copending application Serial No. 706,688, filed January 2, 1958, by Donald H. Noreen et al. which is assigned to the same assignee as the present application.

Inasmuch as the annunciator embodying the features of this invention is comprised of static logic elements having no moving parts, the annunciator is highly reliable in operation and requires substantially no maintenance.

Since certain of the above-described features may be changed without departing from the spirit and scope of this invention, it is intended that all the matter contained in the above description and shown in the accompanying drawings should be considered as illustrative only.

I claim as my invention:

1. In an annunciator: an indicator; a two input AND element for operating the indicator; a first OR element having its output connected to one input of the AND element; a second two input OR element having its output connected to the other input of said AND element; another two input AND element having its output connected to one input of the first OR element; a source of a pulsating signal having its output connected to one input of the second OR element; a MEMORY element having two inputs, a first output connected to one input of the said another AND element, and having another output connected to the other input of each of the first OR element and the second OR element; a NOT element having its output connected to one input of the MEMORY element; a normally opened condition responsive switch for providing a signal to the other input of said another AND element and to the NOT element; and acknowledgment means including a normally opened switch operable to provide a signal to the other input of the MEMORY element.
2. In an annunciator: an indicator; a single input AND element for operating the indicator; a first two input OR element for providing a signal to the AND element; a two input AND element for providing a signal to one input of the first OR element; a source of a pulsating signal for providing a signal to one input of the two input AND element; a NOT element for providing a signal to the other input of the two input AND element; a second OR element for providing a signal to the NOT element; a normally closed condition responsive means normally providing a signal to one input of the second OR element; a MEMORY means for providing a signal simultaneously to the other input of each of the first OR element and the second OR element and having one input for receiving the condition signal and another input; and, acknowledgment means including a normally opened switch for providing a signal to the other input of the MEMORY element.
3. In an annunciator: an indicator; a two input AND element for providing a signal to the indicator; a first two input OR element for providing a signal to one input of the AND amplifier; a second two input OR element for providing a signal to the other input of the AND element; a source of a pulsating signal for providing a signal to one input of the first OR element; a single input AND element for providing a signal to one input of the second OR element; a NOT element for providing a signal to the single input AND element; a third two input OR element for providing a signal to the NOT element; a MEMORY element having two inputs for providing a signal to one input of the third OR element and to one input of the first OR element; condition responsive means including a normally closed switch for providing a signal to the other input of the third OR element and to one input of the MEMORY element, and having one input for receiving the condition responsive means signal; acknowledgment means including a normally opened switch for providing a signal to the other input of the MEMORY element.
4. In an annunciator: an indicator; a two input AND element for providing a signal to the indicator; a first two input OR element for providing a signal to one input of the two input AND element; a second two input OR element for providing a signal to the other input of the two input AND element; a source of a pulsating signal for providing a signal to one input of the first OR element; a condition responsive means including a normally opened switch for providing a signal to one input of the second OR element; a MEMORY element having two inputs for providing a signal to the other input of each of the first and second OR elements in response to

receipt of a signal at one input of the MEMORY element; an acknowledgment means including a normally opened switch and operable to provide a signal to said one input of the MEMORY element; a NOT element for providing a signal to the other input of the MEMORY element and having its input responsive to the condition responsive means.

5. In an annunciator: an indicator; a single input AND for providing a signal to the indicator; a first two input OR element for providing a signal to the AND element; a NOT element for providing a signal to one input of the first OR element; a second two input OR element for providing a signal to the NOT element; a source of a pulsating signal for providing a signal to one input of the second OR element; a MEMORY element having two inputs for providing a signal to the other input of the first OR element in response to a signal at one of its inputs; acknowledgment means including a normally opened

switch for providing a signal to one input of the MEMORY element; and a condition responsive means including a normally closed switch for providing a signal simultaneously to the other input of the MEMORY element and the other input of the second OR element.
